(57) **CLAIM**

We claim the ornamental design for a smart lamp, as shown and described.

DESCRIPTION

FIG. 1 is a perspective view of the smart lamp according to an example embodiment.

FIG. 2 is a front view of the smart lamp shown in FIG. 1. FIG. 3 is a back view of the smart lamp shown in FIG. 1. FIG. 4 is a left view of the smart lamp shown in FIG. 1. FIG. 5 is a right view of the smart lamp shown in FIG. 1. FIG. 6 is a top view of the smart lamp shown in FIG. 1; and, FIG. 7 is a bottom view of the smart lamp shown in FIG. 1. The broken lines in the figures show portions of the smart lamp which form no part of the claimed design.

1 Claim, 7 Drawing Sheets
